UNITED STATES PATENT OFFICE.

WILBER T. EWING, OF BERLIN, TENNESSEE.

LUBRICATOR FOR STREET-CARS.

No. 797,188

Specification of Letters Patent.

Patented Aug. 15, 1905.

Application filed April 20, 1905. Serial No. 256,536.

To all whom it may concern:

Be it known that I, WILBER T. EWING, a citizen of the United States, residing at Berlin, in the county of Marshall and State of Tennessee, have invented certain new and useful Improvements in Lubricators for Street-Cars; and I do declare the following to be a full, clear, and exact description of the invention, such as will enable others skilled in the art to which it appertains to make and use the same.

My invention relates to improvements in lubricators for oiling or greasing the flanges of the wheels of street-cars, locomotives, or the like, so that the track-rails may be lubricated at curves, switches, and other points.

The object of the invention is to improve and simplify the construction and operation of devices of this character, and thereby render the same more durable and efficient in use and less expensive to manufacture.

With the above and other objects in view the invention consists of certain novel features of construction, combination, and arrangement of parts, as will be hereinafter described and claimed.

In the accompanying drawings, Figure 1 is a front elevation of my improved apparatus applied to a street-car, the latter being indicated in dotted lines. Fig. 2 is a bottom plan view of one end of a car, showing the application of the invention. Fig. 3 is a detail vertical longitudinal sectional view taken on the line 3 3 in Fig. 2, and Fig. 4 is a detail view showing the mechanism for operating the wheel-engaging brushes.

Referring to the drawings by numeral, 1 denotes the wheels of a car, locomotive, or the like 2, and 3 denotes my improved lubricating device. The latter comprises a pair of brushes 4, which are adapted to engage the flanges of the wheels 1 and which are mounted upon the ends of diverging arms 5. The opposite ends of the latter are mounted, as shown at 6, to permit them to swing, and they are forced apart by a coil-spring 7, so that the brushes 4 are caused to engage the wheels. The said arms are adapted to be drawn together to retract the brushes 4 by a retracting-rod 8 through slots in which said arms 5 project. This bar 8 is slidably mounted and is loosely connected by a link 9 to one arm or member 10 of a double crank 11. The other member or arm 12 of said double crank is connected by a link-rod 13 to

the lower end of an operating-lever 13', the latter being provided with a hand operating-pawl 14, which is adapted to coact with a rod 15, so that said lever may be rocked at any angle to permit the brushes 4 to be held either in or out of contact with said wheels.

Oil, grease, or other lubricant is supplied to the brushes 4 through short discharge pipes or nozzles 16, provided upon the outer ends of a transversely-disposed supply-pipe 17. The latter is connected at its center by means of a T-coupling 18 to a pipe 19, which leads from an oil-supply tank 20, suitably mounted upon the car. The pipes 18 and 19 are suitably supported, as shown at 21 and 22, and in the pipe 19 is located a controlling-valve 23, which is preferably of the usual cylindrical type. This valve is operated by means of a crank 24, provided upon one of the outer ends of its shaft, and connected by a link 25 to the lower end of an operating-lever 26.

The construction, operation, and advantages of my invention will be readily understood without requiring a more extended explanation. It will be seen that by means of this device the motorman or engineer may by operating the levers 26 and 13 readily lubricate the curves or other portions of a track over which his car or train is about to pass.

Having thus described my invention, what I claim as new, and desire to secure by Letters Patent, is—

1. A lubricator for cars or the like comprising a pair of swinging arms, brushes upon said arms, a spring for forcing said arms apart to hold said brushes normally in contact with the flanges of the car-wheels, means for moving said arms to retract said brushes, and means for supplying oil to said brushes.

2. A lubricator for wheels of cars or the like, comprising a pair of pivotally-mounted arms, brushes upon the ends of said arms, a spring for forcing said arms apart to hold said brushes normally in contact with the flanges of the car-wheels, means for moving said arms together to retract said brushes, an oil-supply tank, oil-pipes for conducting oil from said tank to said brushes, a valve for controlling the flow of oil to said pipes and a lever for operating said valve.

3. A lubricator for the wheels of cars or the like, comprising a pair of diverging spring-actuated arms, wheel-engaging brushes

upon the separated ends of said arms, a slide-
able retracting-bar engaged with said arms,
a double crank, a link connecting said bar
with one member of said crank, an operating-
lever, and a link connecting said lever and
the other member of said crank, substan-
tially as described.

In testimony whereof I have hereunto set
my hand in presence of two subscribing wit-
nesses.

WILBER T. EWING.
